UNITED STATES PATENT OFFICE

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY

CEMENTING MACHINE

Application filed January 17, 1924. Serial No. 686,822.

This invention relates to cementing machines, the type of apparatus herein described being especially adapted for operating upon the channels of the insoles of shoes 5 preparatory to laying the channel-flaps.

Objects of the invention are to provide an efficient machine of this character which will be readily adaptable to coating areas of different widths and to applying coatings of 10 different thicknesses, and which will avoid dripping and waste of cement.

A feature of the invention leading to the attainment of these objects involves means for simultaneously varying the dimensions of 15 a casing in which the brush or other applying member rotates, and the effective co-operation between such applying member and its scraper or member which controls the delivery of cement to the work. Such a construction allows, with minimum effort on the part of the operator, the mounting upon the machine of applying members varying in widths, with an automatically attained corresponding variation in the scraper for such 20 applying members. In the illustrated embodiment of the invention, the applying member rotates within a casing, the side walls of which are relatively movable to cause this casing to conform to the brush, while 25 the scraper is movable with one of these walls and is correspondingly shifted across the periphery of the applying member. Preferably, the applying member is movable longitudinally of the shaft which rotates it, and is forced by the movement of one wall 30 into co-operation with the companion wall, so that tight joints are furnished to prevent the leakage of cement between these elements. The casing as a whole is shown as movable 35 transversely of the axis of the applying member to carry the scraper toward and from the periphery of the applying member, to control the cement laid thereby upon the work.

40 The escape of some of the cement at the side of the applying member is unavoidable, and this cement tends to gather upon the movable support of the member, as the hub through which it is rotated. In this connection, a feature of the invention consists in

directing the cement accumulated upon the support toward the applying member, so that such cement is returned and laid upon the work. The preferred means for accomplishing this consists of a scraper co-operating 55 with the support and suitably inclined to cause the return of the cement as the support is moved.

In machines of the kind with which this invention is concerned, it is customary to supply the cement to the applying member from a receptacle which is removable from the frame of the machine. This receptacle has means for controlling the flow to the applying member, which means is utilized to completely shut off such flow upon the separation of the receptacle from the frame. Operators sometimes forget to effect this closure, and much cement is wasted and surrounding objects soiled. A further feature of the invention has to do with means for preventing the removal of the receptacle in predetermined positions of the controlling means. Herein are shown a valve co-operating with a discharge-opening from the receptacle, and 60 means, which may be carried by the machine-frame, for preventing the removal of the receptacle unless the valve is closed.

The accompanying drawing illustrates a particular form of the invention,

Fig. 1 being a side elevation of a channel-cementing machine embodying my improvements, showing one form of work gage;

Fig. 2, a similar enlarged view of the operating elements of the machine, with parts broken away, showing another form of gage;

Fig. 3, a front elevation of these same operating elements;

Fig. 4, a detail in perspective of the cement-applying brush, together with the means for supplying cement thereto and for controlling the flow of said cement;

Fig. 5, a perspective detail, illustrating particularly the valve for the cement tank and the control casing associated with the applying brush;

Fig. 6, a vertical transverse section upon the line VI—VI of Fig. 2, through such valve and the adjacent elements, and

Figs. 7 and 8 are details showing typical

pieces of work positioned against the applying member by alternative guides or gages.

At 10 appears a standard having, secured upon its upper extremity, a casing 12 for the actuating elements of the apparatus, power being furnished thereto by a motor 14 bolted upon one side of the casing. The motor-shaft 16 is connected through reducing gearing 18 to a shaft 20 journaled in the wall of the casing 12 opposite the motor-shaft. Carried by the shaft 20 is an applying member, preferably furnished by a brush 22 rotatably connected to the shaft, while longitudinally movable on and readily separable from it, by a pin 24 projecting from said shaft and entering a longitudinal slot 26 in the hub 27 of the brush. Associated with this applying member is a yieldable channel-flap-guide and flap-lifting finger 28, generally corresponding in character to that of United States Patent No. 1,004,705, Stanbon, Oct. 3, 1911, save that in the present device, the means for supplying liquid to the flap is omitted. This guide is carried upon a shaft 30 rotatable in the casing 12 above the shafts 16 and 20, and vibrated through an arm 32 fixed upon it and having at its lower extremity a yoke 34 embracing a cam 36 fast upon the motor-shaft 16.

To supply the brush with cement, there is mounted upon the top of the casing 12 a tank or receptacle 38 having a cover 40 forming a tight closure, and, at the bottom, downwardly inclined walls 42 (Fig. 2) converging to an opening 44 (Fig. 5). This opening communicates with a delivery-opening 46 formed above the brush in a horizontal arm 48 formed upon the upper portion of the casing 12. The tank 38 is made readily removable, so that it may be taken from the machine for storage at night, to lessen the fire-risk, and is fixed in place upon the casing 12 by opposite pins 50, 50. In a recess 52 (Fig. 6), located at the under side of the tank 38 beneath the opening 44, is a valve having a plunger 54 movable back and forth across the opening, so that such plunger may completely close it, or may vary the area to control the amount of cement discharged. The end 56 of the plunger is shown as inclined upwardly and rearwardly, considering the direction of movement for closure, this inclination reducing the resistance to the forward travel of the plunger. Connected at 58 to the valve-plunger is a lever 60 (Fig. 5), fulcrumed at 62 upon the tank. The rear extremity of this lever beyond the fulcrum has threaded through it a stop-screw 64, which contacts with a surface upon the tank. By adjusting this screw, the amount of closure of the opening 44 may be determined to regulate the flow of cement, or upon a sufficient backing-off of the screw, the valve may be closed completely. Extending laterally from the horizontal arm 48 near the bottom of the tank, beneath

and then vertically past and over the upper face of the lever 60, is a retaining member, furnished by a hook 66. The extension of this hook-portion over the lever is such that when the valve is closed, the lever is free from engagement with the hook, so that the tank may be taken from the machine. If, however, the valve-plunger is so positioned that the outlet of the tank is open, the lever comes beneath the hook, rendering it impossible to raise the tank from the frame, and thus warning the operator of the condition of the valve.

Holding the delivered cement in temporary association with the upper peripheral portion of the brush is a casing C. This casing is preferably carried by a slide 68 (Fig. 2) movable in ways 70 in the arm 48. The casing includes a wall 72 depending from the slide 68 and having its inner surface in a plane substantially parallel to the inner side of the brush and extending at its edge into close proximity with the brush-hub (see Fig. 6). The forward edge of the wall 72 (Fig. 4), or that edge toward which the top of the brush rotates, is inclined at 74 downwardly and inwardly, and has bearing against it a scraper 76 (Fig. 5), the reduced lower extremity of which approaches the periphery of the brush, to form part of the casing C and make a contracted throat through which the cement is carried downwardly to the work. The scraper 76 is adjustably held in place upon the slide 68 and hence upon the wall 72, with its inner face pressed against the edge 74 of the wall 72, by a screw 78 passing through a horizontal slot in the scraper and being threaded into the slide. This connection permits the scraper to be adjusted transversely of the brush, to correspond to its width, thus varying its effective co-operation with the brush. Carried by and integral with the scraper is a wall 80 (Fig. 4) furnishing the opposite side of the casing C from the wall 72, and having its inner face similarly related to the opposite side of the brush. Upon this wall 80 is a depending flange 82 (Fig. 2), which contacts with the body of the brush. When the scraper is adjusted across the applying surface, by virtue of the slotted connection to the portion 74 of the slide, the wall 80 is correspondingly moved toward the wall 72 to vary the width of the casing C, the flange 82 pushing against the brush so that the inner side of the brush is brought into close contact with the face of the wall 72, while at the same time the outer wall 80 is maintained against the outer side of the brush. In this way, by a single adjustment by the operator, the casing is caused to exactly fit the brush laterally, with tight joints at its sides, and the scraper is made effective over the particular peripheral width of the brush employed. At the upper portion of the casing, a surface 84 (Fig. 4) at the top of the scraper 76 and

the wall 80 bears closely against a parallel surface upon the under side of the tank 38, so that there can be no leakage at this point while movement of the casing C is occurring by the shifting of the slide 68. To effect this movement of the slide, there is provided a bracket 86 projecting from the arm 48 on the casing 12 and having turning but held against endwise movement in it, a horizontal screw 88 engaging a threaded opening 90 in the end of the slide. When this screw is turned, the slide is moved to alter the space between the lower edge of the scraper and the periphery of the brush (Fig. 6). This controls the amount of cement removed from the casing, to which it has been delivered through the openings 44 and 46, and consequently varies the thickness of the coating applied to the work. A lock-nut 92 may be provided to retain the screw 88 in its adjusted position. The side of the casing C opposite the scraper 76 and the delivery-opening 46 is open, so that this movement of the casing is not interfered with. It is desired to point out that the line of co-operation between the scraper and brush is above the horizontal plane through the axis of the latter. Consequently, there is no tendency for cement to drip from this point upon the work or the floor; it instead remaining upon the bristles to be applied to the work, or carried back to the casing at the upgoing side of the brush.

In spite of the effectiveness of the closure at the sides of the casing, some cement will escape, and, gathering upon the hub 27, will tend to drip from the machine. To prevent this, a fixed blade 94 (Fig. 5) is mounted at 96 upon the frame, it having an edge 98 curved to conform to the brush-hub and lying in proximity to it. This blade, at its line of contact with the hub, is inclined toward the brush in the direction of rotation. This causes the cement upon the hub, as it moves into contact with the scraper, to be diverted toward the side of the brush, which takes it up and, by the rotational drag, moves it toward the periphery into the casing C, from which it is utilized.

The illustrated apparatus is employed in the manner customary with channel-cementing machines, the shoes operated upon being placed with the under side of the open flap 112 upon the top of the finger 28, with the upper side, or what, in the finished shoe, is the interior of the flap, in contact with the brush 22 as in Fig. 7. The operator selects a brush of such width that it will apply the cement from its periphery over the exposed face of the flap and over the wall of the sole 110 with which this face is to contact when the channel is laid. After applying this brush to the machine, it is only necessary for the operator to press the wall 80 and scraper 76 inwardly, so that the depending flange 82

forces the brush against the opposite wall 72. Then, upon securing the parts in place by the screw 78, the casing and scraper will have been exactly adjusted to the transverse dimensions of the brush. The valve 54 is opened sufficiently to keep the casing constantly supplied with cement from the receptacle 38, without overflowing rearwardly, and the slide 68 moved by the screw 88 to give the proper width of throat at the lower edge of the scraper to insure the desired thickness of cement upon the periphery of the brush. The shoe is advanced by the operator over the flap-lifting-finger 28, which guides the work and holds the flap in contact with the brush, at the same time smoothing out its irregularities. For operating upon soles 120 without channels, the finger 28 may be removed, and a work support 100 (Figs. 1 and 2) brought into use as in Fig. 8. This work support has a rounded upper face (not shown) and is supported by a screw 102, passing through a slot 104 in a projection from the casing 12. It has upon its outer or upper face a gage-surface 106, with which the edge of the sole to be operated upon may contact. When the finger 28 is in use, the work support 100 hangs vertically from its supporting screw as in Fig. 2; but when this support 100 is to be employed, it is raised to a horizontal position, and there fastened by its screw, the slot 104 permitting the gage surface 106 to be correctly located to determine the area to be cemented by the brush.

Having described my invention, what I claim as new and desire to secure by Letters Patent of the United States is:

1. In a cementing machine, a rotatable applying member, a cement-receptacle delivering to the applying member, a casing in which the applying member rotates and which is provided with a cement-controlling member co-operating with the applying member, and means arranged to vary simultaneously the dimensions of the casing and the effective co-operation between the applying member and controlling member.

2. In a cementing machine, a rotatable applying member, a cement-receptacle delivering to the applying member, walls at each side of the applying member, said walls being movable relatively to each other, and a scraper movable with one of the walls for co-operation with the applying member.

3. In a cementing machine, a rotatable brush, a cement-receptacle delivering to the brush, and a casing in which the brush rotates, said casing having a side wall, a scraper for the brush movable with respect to said side wall and an opposite side wall carried by and movable with the scraper.

4. In a cementing machine, a shaft, an applying member rotatable with the shaft but free to move longitudinally thereof, and opposite side walls between which the apply-

- ing member rotates, one of said walls being movable toward and from the other and contacting with the applying member to hold it in co-operation with the other wall.
5. In a cementing machine, a shaft, an applying member rotatable with the shaft but free to move longitudinally thereof, opposite side walls between which the applying member rotates, one of said walls being movable toward and from the other and contacting with the applying member to hold it in co-operation with the companion wall, and a cement-controlling member co-operating with the applying member and movable with the wall.
10. 6. In a cementing machine, a shaft, an applying member rotatable with the shaft but free to move longitudinally thereof, a scraper co-operating with the periphery of said applying member and opposite side walls between which the applying member rotates, one of said walls being mounted upon said scraper and movable toward and from the other and contacting with the applying member to hold it in co-operation with the companion wall.
20. 7. In a cementing machine, a cement-receptacle, an applying member receiving cement from the receptacle, a casing for the applying member mounted to move relatively to the receptacle, a rotatable member engaging the casing to effect its movement and a cement-controlling member movable by the casing to different distances from the periphery of the applying member.
30. 8. In a cementing machine, a cement-receptacle, an applying member rotatable beneath the receptacle, and a casing movable relatively to the receptacle and having walls at opposite sides of the applying member, and a scraper movable with the casing toward and from the periphery of the applying member.
40. 9. In a cementing machine, a cement-receptacle, a brush rotatable beneath the receptacle, an element providing a side wall movable in a direction substantially parallel to one side of the brush, a scraper for the brush movably mounted upon said element so that it is adjustable with respect to said wall, and a wall carried by the scraper at the opposite side of the brush.
50. 10. In a channel-cementing machine, the combination with a frame having an opening and ways adjacent to the opening, of a receptacle mounted on the frame and delivering to the opening an applying brush movable upon the frame beneath the opening, and a casing for the brush movable in the ways.
60. 11. In a channel-cementing machine, the combination with a frame having an opening and ways adjacent to the opening, of a receptacle mounted on the frame and delivering to the opening an applying brush

movable upon the frame beneath the opening, a wall movable upon the ways in a direction substantially parallel with one side of the brush, and a wall adjustably secured to that first mentioned and movable toward and from the opposite side of the brush.

70. 12. In a channel-cementing machine, the combination with a frame having an opening and ways adjacent to the opening, of a receptacle mounted on the frame and delivering to the opening an applying brush movable upon the frame beneath the opening, a wall movable upon the ways in a direction substantially parallel with one side of the brush, a scraper adjustably secured to said wall for movement transversely of the periphery of the brush, and a wall carried by the scraper and co-operating with the brush at the opposite side of the wall first mentioned.

75. 13. In a cementing machine, a rotatable support having a cylindrical surface, an applying member mounted to extend out therefrom for rotation therewith, and fixed scraper means co-operating with a portion 90 of said cylindrical surface and positioned to direct cement lodged on said surface toward the applying member.

80. 14. In a cementing machine, a rotatable brush having a hub, a cement-receptacle situated above and delivering to the brush, and a scraper co-operating with the brush-hub and being inclined to direct cement thereon toward the brush.

85. 15. In a cementing machine, the combination with a frame, of a cement-receptacle 100 removably mounted thereon, an applying member receiving cement from the receptacle, means for controlling the flow of cement to the applying member, and means for preventing the removal of the receptacle in predetermined positions of the controlling means.

90. 16. In a cementing machine, the combination with a frame, of a cement-receptacle 105 removably mounted thereon and having a discharge-opening, an applying member receiving cement from the opening, means for closing the opening, and means for preventing the removal of the receptacle in the open position of the closing means.

100. 17. In a cementing machine, the combination with a frame, of a cement-receptacle 110 removably mounted thereon and having a discharge-opening, a valve associated with the opening, and means carried by the frame for engagement with the valve to prevent removal of the receptacle.

110. 18. In a cementing machine, the combination with a frame, of a cement-receptacle 115 removably mounted thereon and having a discharge-opening, a valve associated with the opening, a lever for actuating the valve, and a member upon the frame overhanging the lever when the valve is open.

19. In an applying apparatus, a rotatable support, an applying member thereon movable by the support having an end surface adjacent to the support and extending outwardly therefrom at an angle to said support, means for supplying a coating substance to said applying member, and a deflecting member cooperating with the rotatable support, and positioned at an angle to the surface of the support and to the axis of rotation to deflect back toward the end surface of the applying member any coating substance appearing on said support, upon relative movement of the support and the deflecting member, by reason of diversion of the coating substance by said deflecting member under the drag of the movable support.

20. In testimony whereof I have signed my name to this specification.

JOHN W. COSGROVE.
